JOHN RYFFEL, OF BROOKLYN, NEW YORK

CONTROLLING APPARATUS

Application filed November 2, 1927. Serial No. 230,584.

The invention relates to combustion controlling apparatus for furnaces, more especially of the household type such as the ordinary steam boiler furnace in common use—although, with certain modifications of the heating system, the novel control may be applied equally well to hot water heating apparatus; and comprises a supplementary regulating attachment therefor.

The invention is adapted especially to heating apparatus in which there is employed a forced draft for the fire; and it has for its object to accelerate the cut-off action of the usual regulator employed—as the pressure controlled diaphragm apparatus of a boiler, for example, thus equipped for forced draft burning—and to check for a predetermined period throwing into operation again the draft producing apparatus, so that overheating by said furnace will be avoided and economy in fuel consumption effected. A further object of the invention resides in the construction of apparatus which may readily and inexpensively be installed and which makes it possible to equip household types of boilers with forced draft mechanism, permitting thereby of the utilization of cheaper grades of coal, such as No. 1 buckwheat and rice sizes.

A still further object resides in the provision of a contact element and circuit therefor whereby the controlling electric motor for the draft-producing apparatus may be manually controlled at the boiler as well as from a point remote therefrom in addition to the automatic control during normal operation.

To this end, the invention comprises a suitably enclosed mercury switch mechanism which is arranged to be oscillatably mounted on the usual controlling bar or lever of the pressure-controlled diaphragm apparatus generally associated with household types of steam boilers, provision being made to limit the extent of oscillation of the contact device relatively to said bar.

The nature of the invention will best be understood, however, when described in connection with the accompanying drawings, in which:

Fig. 1 shows in side elevation the novel

regulator illustrated, for example, as associated with a steam boiler and blower apparatus for the furnace thereof.

Fig. 2 is a longitudinal enlarged section through the circuit controlling member as mounted upon the pressure-controlled dia-

phragm bar member.

Fig. 3 is a diagrammatic view illustrating the electrical connections involved.

Referring to the drawings, 10 designates a steam boiler of the ordinary household type but in connection with which there has been installed a blower 11 for introducing air under pressure into the ash pit 12 of the furnace. The said blower is driven by an electric motor 13 to which power is supplied by the leads 14 through a suitable switch, as the single-pole switch 15 located in proximity to the furnace, as shown, so that when it is desired to remove ash the blower mechanism may be shut off temporarily. A further switch, as the single-pole switch 16 located at a point remote from the furnace room, may be included in the circuit so that the furnace may conveniently be shut down by cutting off the blower 11, as in the evening, and likewise starting it again in the morning by closing the circuit at the switch 16.

A further contact device is included in the motor circuit; and it is necessary that all three of these contact devices be closed before the motor 13 can be energized to operate the blower 11. The last-named contact device is arranged to be installed on the boiler, or rather, on the bar or lever 20 of the pressure-controlled diaphragm apparatus 21 of said boiler; and said device is enclosed within a protective metal casing 22. The latter, in turn, is pivotally secured to the said bar 20 through an arm 23 extending downwardly therefrom and at a point on one side of the fulcrum 24 provided on the pressure-controlled diaphragm member 21, the bar 20 being provided with the usual adjustable regulator weight or weights 25 for determining the pressure under which the said bar shall tilt. Adjustable buffer members, as the plates or stops 26, are provided along opposite ends of the casing 22 to limit the extent of oscillation of the casing or contact

device thereof relatively to said bar on either side of the pivotal point 27 through contact of the lower end of said stops with the upper surface of the bar 20. This obviates undue oscillation of the casing and also provides for the elevation of its depressed end as the corresponding end of the bar 20 moves upwardly under the action of the regulator diaphragm 21. When the casing has been swung upwardly to an extent sufficiently to bring arm 23 beyond a perpendicular plane, the said casing will drop over under its own weight to the opposite side of the pivotal point 27 and with a rapid or snap action.

15 This action is utilized to make a quick contact or to rapidly break the same as the case may be; and to this end there is mounted within the casing a suitable container as the 20 L-shaped glass tube 30 containing mercury 31 but which does not completely fill said tube. At the one end of the tube or foot portion of the L-member two contact elements 32 are introduced and sealed into the said tube, the 25 same extending when the tube is depressed at the opposite end in manner such that the mercury is not in contact with said elements, or at least not in contact with one of the same. These contact elements are included in series 30 in circuit with the switch devices 15 and 16; and unless the circuit is closed at said elements 32, as well as the aforesaid devices 15 and 16, no current will be supplied for operating the motor 13.

35 In the tilted position shown in Fig. 1 of the drawings, the mercury 31 is substantially free of both of the said elements 32 and no contact is made thereat so that the blower is cut off from the furnace and the heat of the same will, therefore, gradually fall off. When 40 this has reached a predetermined degree, casing 22 will be elevated at the previously depressed end under the action of the gradually upwardly moving bar portion until arm 23 is 45 upon the opposite side of the perpendicular, whereupon the casing drops until it is stopped through contact of the corresponding stop member 26 with the upper surface of the opposite end of the bar. By this action, 50 the mercury 31 flows rapidly to the other end of the tube covering both of the contact elements 32 and closes thereby the circuit through the same. This, if the other contact devices 15 and 16 are closed, will cause the 55 blower to start up again; and as the temperature gradually increases the said contact end of the casing will be elevated under the upward motion of bar 20 until arm 24 rocks past 60 the perpendicular position, whereupon said casing with tube drops quickly downwardly into the depressed position shown, making also thereby a quick break of the circuit at the contact elements 32. This cuts off the current to the motor and shuts down the blower,

the cycle being repeated as the furnace cools down.

By this expedient, a very simple and substantial contact-making device may be associated with the usual regulator bar or lever 70 and is actuated thereby to control the furnace operation. The casing 22 embodies a substantial and suitably sealed member, while the glass or like container therein for the contact-making mercury is absolutely sealed against foreign matter and the contacts 32 will therefore always be in the best condition for making or breaking contact. The snap effect or quick action of break and make, due to the sudden over-balancing, further insures continuous operation and long life of the contact elements 32.

75 I claim:

1. A contact controlling device, comprising a tilttable support, means to oscillate the same in accordance with conditions to be regulated by the contact device, a casing pivotally mounted upon and carried by said tilttable support, and a mercury contact member mounted within said casing.

80 2. A contact controlling device, comprising a tilttable support, means to oscillate the same in accordance with conditions to be regulated by the contact device, a casing pivotally mounted upon and carried by said tilttable support, the ends of the casing being adapted for engagement with said support to limit the extent of its pivotal movement and for effecting elevation of an end with corresponding movement of the support, and a 90 mercury contact member mounted within said casing.

95 3. A contact controlling device, comprising a tilttable support, means to oscillate the same in accordance with conditions to be 100 regulated by the contact device, a casing pivotally mounted upon and carried by said tilttable support, adjustable stops extending from the ends of the casing toward the support to limit the extent of its pivotal movement and for effecting elevation of an end of the casing with corresponding movement of the support, and a mercury contact member 105 mounted within the said casing.

110 In testimony whereof I affix my signature. 115
JOHN RYFFEL.
